MACHINE FOR SEWING PIPING TO TWO SUPERPOSED LAYERS

John E. Walsh, Beverly, Mass., assignor to United Shoe Machinery Corporation, Flemington, N. J., a corporation of New Jersey

Application June 6, 1951, Serial No. 230,147

14 Claims. (Cl. 112—127)

1

The present invention relates to improvements in sewing machines for operating upon two superposed layers of material, the edge of one of which requires trimming to bring it into register with the edge of the other and between which layers the flange portion of a piping strip is to be sewed with a bead on the strip drawn into close fitting relation to the edges of the material. In certain respects the present invention is an improvement over that disclosed in United States Letters Patent No. 1,820,829, granted August 25, 1931, upon application of E. J. Ray.

The machine of the invention is intended to sew the lining to the upper of a shoe and to insert into the seam a piping strip which conceals the edges of the lining and upper and provides an ornamental finish to the edges of the material operated upon.

An object of the invention is to provide a machine capable of trimming the surplus from one edge of two superposed layers of material to bring their edges into register, of inserting in an advantageous manner between the layers the flange portion of a piping strip and thereafter of sewing the edges and piping strip together in a single continuous operation. A secondary object is to provide such machine with suitable and convenient adjustments and readily accessible operating mechanisms for the different work performing instruments, including a knife for trimming the material operated upon and a piping strip guide for positioning the strip in proper relation between the layers of material.

In its illustrative form the machine is equipped with the usual stitch forming devices, an edge gage, a trimming knife provided with its cutting edge disposed to cut the material operated upon, a work support and a member located along the line of the seam inserted in advance of the point of operation of the stitching forming devices to separate the layers of the material so that the knife will trim one layer only, in which a guide also is provided for a piping strip acting to project the flange between the layers of the material close to the layer separating member. In one form of this feature the guide comprises a wheel about which one edge of the piping strip is wrapped. Preferably, the wheel is dished and rotatably mounted on an inclined axis so that one edge of the wheel is substantially above the level of the material while the other edge of the wheel lies approximately in the plane of the material.

These and other features of the invention, as hereinafter described and claimed, will be ap-

2

parent from the following detailed description of a preferred construction taken in connection with the accompanying drawings, in which:

Fig. 1 is a view in side elevation looking from the right of a portion of a sewing machine embodying the features of the present invention;

Fig. 2 is a plan view on an enlarged scale of the lower portion in the machine illustrated in Fig. 1;

Fig. 3 is a detail plan view of a portion of the mechanism for locking a knife actuating finger in knife engaging position;

Fig. 4 is a sectional view of the parts illustrated in Fig. 3 taken along the line IV—IV;

Fig. 5 is a sectional view on an enlarged scale, including two superposed layers of material in the process of being operated upon as seen along the line V—V of Fig. 2;

Fig. 6 is a sectional view taken along the line VI—VI of Fig. 5;

Fig. 7 is a similar sectional view taken along the line VII—VII of Fig. 5;

Fig. 8 is a detail plan view showing the manner of operation of the piping strip guide and a portion of the edge gage shown in section;

Fig. 9 is a similar view of the same parts omitting the edge gage and a cover for a piping strip supporting and layer separating plate;

Fig. 10 is a detail perspective view on a further enlarged scale of a trimming knife supporting slide in the machine;

Fig. 11 is a similar view of the trimming knife; and

Fig. 12 is an enlarged sectional view taken along the line XII—XII of Fig. 1.

The machine illustrated in the drawings is intended to finish the combined edges of two layers of material disposed in superposed relation to each other with one edge projecting beyond the other, by inserting and securing between them a beaded piping. In order to insure a workman-like result the wider layer of material is trimmed to bring it into register with the narrower layer and the bead on the piping is brought into accurate engagement with the trimmed edges of both layers. The layers and piping are combined by sewing, the machine being equipped with a straight eye-pointed needle and other lockstitch forming devices as well as with an edge trimmer similar to that of United States Letters Patent Re. No. 7,860, reissued August 28, 1877, upon application of L. L. Barber.

Referring more particularly to Fig. 1 of the drawings the needle is illustrated at 2 and operates with other stitch forming devices (not

shown) to sew together the edge portions of superposed layers of material comprising a shoe upper 4 (see Figs. 5 and 6) and its lining 6 supported at the operating point of the needle by a work plate 8 and a pair of work clamping and feeding rolls 10 and 12, the lowermost one of which is mounted for rotation below the work plate and is driven by a bevel gear 14 (Fig. 1) meshing with bevel teeth on the side of the roll 12. According to usual shoe making practice the lining for the upper has a wider edge than the upper itself and projects therefrom, the lining usually being attached to the upper with the edge of the upper at a distance from the edge of the lining. To guide the narrower layer of upper material and wider layer of lining material the edge of the upper contacts a gage 16 located to bring the upper edge into vertical alignment with a vibrating trimming knife 18 mounted on the machine in close proximity to the edge gage 16 for reciprocating movement along the rearward side of the work plate. The knife accordingly trims the edge of the wider lining layer which projects beyond the upper into accurate register with the edge of the upper. To enable the knife to trim the lining without engaging the upper the two layers of material are separated at the point of operation of the knife by a piping strip flange supporting member 20 projecting between them with its work engaging end located along the seam line a short distance in advance of the point of operation of the stitch forming devices and between the trimming knife and the sewing point.

To apply a piping strip to the edges of the material it is impossible to employ the usual form of piping strip guide on account of the location of the trimming knife close to the sewing point, it being necessary to insert the piping strip within the short distance between the edge of the trimming knife and the sewing point. In inserting the piping strip within this short distance an improved form of guide has been provided especially effective in its action of projecting the flange portion of the strip to its full width between the edges of the layers operated upon within the limited distance along the edges available for this purpose.

The piping strip guide of the present invention comprises a dished wheel 22 having a circular concavity about its rim within which the piping strip is retained, the strip being wrapped through an arc about the edge of the wheel 22 of about 180°. The wheel is rotatably mounted on a frictionless bearing 24 best shown in Figs. 5 and 6, disposed with its axis of rotation inclined with respect to the plane of the layers of work material engaging the work supporting surface of the work plate 8. The guide wheel acts to project the flange of the piping strip between the separated layers of material operated upon at a point along the seam line between the trimming knife and the sewing point. The inclination of the guide wheel is such that one edge of the wheel lies substantially above the level of the work material and the other edge of the wheel lies in the plane of the material. To retain the flange of the piping strip within the concavity at the edge of the wheel as the wheel rotates the supporting member 20 surrounds the periphery of the wheel with a guiding surface arranged parallel to and in line with the dished rim of the wheel.

The piping strip flange supporting member 20 is in a form of a recessed plate carried by an adjustable mounting block 26 (see Fig. 1) slid-

able in two directions at right angles to each other for varying the projection of the piping strip flange between the layers of material and for centering the flange on the piping strip accurately between the layers. The block 26 and the piping supporting plate also serve as a mounting for an inclined spindle 28 passing through the bearing 24.

To confine the flange of the piping strip in the recess of the supporting plate, the supporting plate has secured to it a cover 30 also surrounding the periphery of the guide wheel 22. The cover is disposed in spaced parallel relation to the supporting plate and also is arranged to enter between the layers of the work material in close proximity to the layer separating end of the supporting plate. In this way engagement of the flange on the piping strip is kept from contact with either layer of the material until the piping strip enters to the extent of its full width between the layers, the bead of the strip being pressed firmly against the edges of the upper and lining so that close contact between the parts is obtained. As shown in the upper sectional illustration of Fig. 6 of the bead of the strip is formed with shoulders, indicated at 32, extending at an acute angle to the flange. When the strip reaches the lower edge of the wheel and its flange is pressed widthwise between the upper and lining layers, the shoulders on the bead are pressed firmly against the edges of the layers and flexed away from the flange to give a more positive contact with the edges of the layers, as shown in the lower sectional illustration of the strip in this figure.

To maintain the edge gage 16 uniformly in yielding engagement with the edge of the upper 4 the edge gage is constructed in the form of a reversely bent plate secured to a block 34 (see Fig. 1) having a pivotal mounting 36 in ears projecting from the cover plate 30. The edge gage plate has a horizontal flange portion projecting above the margin of the upper and an edge contacting nib 37 projecting downwardly from the flange. The central portion of the plate has a slot 38 through which passes one end of the inclined spindle 28. Surrounding the upper end of the spindle is a compression spring 40 confined between a check nut 42 on a threaded portion of the spindle and the upper surface of the gage plate in a manner to press the flange of the gage uniformly with resilient pressure against the marginal portion of the upper 4. At the same time irregularities in the thickness of the material operated upon will enable the gage to be swung clear of the irregularities or a new piece of work material to be forced beneath it in bringing the work to properly adjusted operating position. The work engaging end of the gage 16 is offset to clear the needle path.

For adjusting the piping strip guide in two directions at right angles to each other the block 26 is mounted for sliding movement in a vertical guideway portion of a horizontally sliding block 44 (see Figs. 1 and 12). The vertical position of the block 26 in the guideway of the block 44 is adjusted by a thumb screw 46 threaded into the block 26 and having the under surface of its head engaged by the upper edge of the block 44. To insure engagement of the head on the thumb screw 46 with the block 44 and to lock the block 26 in vertically adjusted position the thumb screw 46 is engaged by the lower end of a second thumb screw 48 threaded into a yoke 50 secured to the upper ends of the guideway in the block 44. The

thumb screw 48 enables the head on the thumb screw 46 to be clamped securely against the upper surface of the guideway in the block 44. To prevent release of the clamping thumb screw 48 it carries a check nut 52 acting against the upper surface of the yoke 50.

The sliding block 44 is supported in a pivotally mounted carrier 54 restrained in position by the engagement of a latch 56 comprising a lever fulcrumed on a screw 58 threaded into a fixed bracket 60 projecting rearwardly from the frame of the machine. Movement of the horizontally sliding block 44 is adjusted by a thumb screw 62 rotating in a bearing 64 on the carrier 54, the thumb screw 62 being confined against lengthwise movement in the bearing between the head of the thumb screw and a collar 66 on the screw. The thumb screw 62 enters a threaded opening in the block 44 so that rotation of the thumb screw moves the block in the horizontal guideway of the carrier. The carrier is pivoted at 68 to swing on the bracket 60 about a horizontal axis and upon disengagement of the latch 56 with the carrier the entire piping strip guide and its mounting may be swung from the solid line position of Fig. 1 to the raised dot-dash line position, the underlying parts of the machine then being exposed and readily adjusted or replaced.

The trimming knife 18 is best shown in Fig. 11 and consists of a thin narrow width of sheet steel provided with a hooked cutting edge 70 and a perforated tongue 72 arranged to be received in a recessed area of a sliding dovetail block 74. The block 74 has a dowel pin 76 located to enter the perforation in the tongue 72. When in place on the block the knife slides in a vertical position against a rearward face of the work plate 8. To support the knife block 74 a dovetail guideway is formed at the rear lower portion of the work plate 8. For reciprocating the knife the block 74 has a notch 78 engaged by a ball ended finger 80 (see Figs. 1 to 3) pivotally mounted on a horizontal oscillating arm 82 secured to a hollow vertical rockshaft 84 rotating at its upper end in bearings in the bracket 60 and at its lower end in a bearing 86 in the machine frame. At the lower end of the rockshaft is clamped an arm 88 having at its free end a spring pressed plunger 90 engaging a perforation in one arm of an oscillating lever 92 secured to a vertical shaft 94 rotatable in bearings 96 in the machine frame, said bearings being formed in alignment with the bearings for the rockshaft 84. Another arm of the lever 92 is pivotally connected to a yoke 98 within which is slidably mounted a rectangular block 100 rotatable on a screw 102 threaded eccentrically into the end of a rotating horizontal shaft 104 driven from a source of power separate from that for operating the machine, the shaft 104 being rotatable in the machine frame.

The pivotal mounting of the finger 80 on the arm 82 includes a pin 106 passing through lugs on a horizontal plate 108 and through the rearward end of the oscillating arm 82, as best shown in Fig. 3. The plate 108 forms a support for an elbow piece 110 to which it is secured and which in turn carries the knife actuating finger 80. The rearward end of the plate 108 is bent downwardly to serve as a stop with a pair of rearward projections from the arm 82 (Fig. 1) acting to limit the swinging movement of the knife actuating finger upwardly away from the block 74. To enable the plate 108 and the finger 82 to be raised easily the pin 106 has surrounding it a torsion

spring 112 engaging at its ends respectively the arm 82 and the plate 108.

For locking the knife actuating finger to the oscillating arm 82 so that the finger will not be raised and disengaged from the knife supporting block 74 during operation of the machine the arm 82 has two opposed undercut recesses 114 at opposite sides of the plate 108 and in these recesses are disposed a pair of horizontal latch arms 116 pivoted at 118 to the arms 82. At their free ends the latch arms 116 are provided with hooks which overlap the side edges of the plate 108 and are connected together by a tension spring 119. When in the position of Fig. 3, the plate is locked in operative position with the finger 80 engaging the notch in the knife block 74.

To unlock the finger 80 for vertical swinging movement out of engagement with the knife block 74 after the piping strip guide carrier is swung to its raised position the latch arms 116 have lug portions disposed midway between their ends in a position to be engaged by a conical enlargement on a manually actuated vertical slide rod 120 mounted within the rockshaft 84 (see Fig. 4). The slide rod 120 has a rounded upper end for engagement by the operator's finger and is arranged when depressed by the operator to separate the latch arms 116 from engagement with the finger carrying plate 108. The finger carrying plate then is freed for upward movement by the spring 112 so that the finger 80 is raised from engagement with the knife block 74.

To prevent the finger 80 from being disengaged from the knife block 74 before the piping strip guide wheel 22 and the layer supporting member 20 are raised from operative positions the carrier 54 acts as a cover for the upper end of the control rod 120. When the carrier is in its lower latched position it blocks access to the manually actuated control rod 120 and prevents the finger carrying plate 108 from being unlatched.

As a further convenience in rendering the knife and supporting block 74 accessible for assembly or disassembly the finger 80 together with the oscillating arm 82 may be swung to one side away from its operative position. For this purpose the plunger 90 is raised from engagement with the perforation in the arm 92, thus providing a disconnectable connection in the arm oscillating mechanism. In the illustrated machine this connection is disconnected at the same time as and in a single operation with the unlocking action of the latch arms 116. To facilitate quick disconnection the rod 120 extends downwardly the entire length of the rockshaft 84 and into an axial passage in the shaft 94. The lower end of the rod is engaged by a compression spring 122 inside the shaft 94 to retain the rod 120 in raised inoperative position. Between the rockshaft 84 and the shaft 94 the rod 120 has a section of reduced diameter which is engaged by one arm of a lever 124 fulcrumed on a shoulder screw 126 carried by the arm 96. The other end of the lever 124 has an opening through which passes the spring pressed plunger 90, the lever engaging the plunger beneath an enlarged head on the plunger. When the rod 120 is depressed to unlock the finger carrying plate 108 the lever 124 also raises the plunger from engagement with the actuating lever 92. The rockshaft is then actuated in a clockwise direction by a spring 128 coiled about the rockshaft when the plunger is raised the ends of the spring being engaged with the machine frame and a

collar 130 on the rockshaft, respectively. The carrier 54 in its latched position not only prevents the finger carrying plate from being unlocked but also prevents disconnection of the disconnectable connections of the knife oscillating mechanism. To return the rockshaft to running position the central portion has clamped to it a wing handle 132.

Disengagement of the finger 80 from the recess in the knife block 74 enables the knife block to be removed from its guideway. With the removal of the knife block from the guideway the knife itself is readily disconnected therefrom and is available for resharpening or replacement.

The nature and scope of the invention having been indicated and an embodiment having been described, what is claimed is:

1. A sewing machine for operating upon two layers of material, the edge on one of which projects beyond that of another, said machine having stitch-forming devices, an edge gage for the narrower layer, a trimming knife for the wider layer mounted in close proximity to the edge gage and disposed along the line of the seam inserted adjacent to and in advance of the point of operation of the stitch forming devices to cut said layer, a work support, and a member located along the line of the seam inserted in advance of the point of operation of the stitch-forming devices to separate the layers of said material and to cause the knife to trim one layer only thereof, in combination with a guide for a flanged piping strip acting along the seam line between the trimming knife and the sewing point to project the flange on the piping strip between the separated layers of material.

2. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide comprising a wheel about which one edge of a piping strip is wrapped mounted between the trimming knife and the point of operation of the stitch forming devices to project a flange on the piping strip between the separated layers of the material.

3. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide located between the knife and the point of oper-

ation of the stitch forming devices comprising a wheel about which one edge of a piping strip is wrapped mounted to project a flange on the piping strip between the separated layers of the material, said wheel having a concavity about its rim for preventing displacement of said strip.

4. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a dished wheel between the knife and the point of operation of the stitch forming devices rotatably mounted about an axis inclined with respect to the plane of the layers of material operated upon to bring one edge of the wheel substantially above the level of the material operated upon with another edge of the wheel lying in the plane of the material.

5. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide comprising a wheel about which one edge of a piping strip is wrapped mounted between the knife and the point of operation of the stitch forming devices to project a flange on the piping strip between the separated layers of the material, and a cover surrounding the periphery of the guide wheel in parallel relation to the layer separating member to confine the flange of the piping strip on the edge of the wheel as the wheel rotates.

6. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide comprising a wheel about which one edge of a piping strip is wrapped mounted between the knife and the point of operation of the stitch-

forming devices to project a flange on the piping strip between the separated layers of the material, and a cover disposed in parallel relation to the layer separating member and arranged to enter between the layers of the material operated upon in close proximity to the layer separating member to prevent engagement of the flange on the piping strip with either layer of material.

7. A sewing machine for operating upon two layers of material, the edge on one of which projects beyond that of another, said machine having stitch-forming devices, an edge gage for the narrower layer, a trimming knife for the wider layer mounted in close proximity to the edge gage and disposed along the line of the seam inserted adjacent to and in advance of the point of operation of the stitch-forming devices to cut said layer, a work support, and a member located along the line of the seam inserted in advance of the point of operation of the stitch-forming devices to separate the layers of said material to cause the knife to trim one layer only thereof, in combination with a guide for a piping strip acting along the seam line between the trimming knife and the point of operation of the stitch-forming devices to project the flange between the separated layers of material, a pivotal mounting for the edge gage to enable the gage to be swung clear of the material operated upon and resilient means for maintaining the edge gage yieldingly in engagement with the untrimmed layer of material.

8. A sewing machine for operating upon two layers of material, the edge of one of which projects beyond that of another, said machine having stitch-forming devices, a vibrating trimming knife mounted in close proximity to the edge gage and disposed along the line of the seam inserted adjacent to and in advance of the point of operation of the stitch-forming devices to cut the material operated upon, a work support and a member spaced from the work support in advance of the point of operation of the stitch-forming devices to separate the layers of said material and located along the line of the seam between the sewing point and the cutting edge of the knife, in combination with a guide comprising a wheel about which one edge of a piping strip is wrapped, mounted between the knife and the point of operation of the stitch-forming devices to project a flange on the piping strip between the separated layers of the material, an edge gage for guiding the narrower edge of the material mounted opposite the point of operation of the knife to cause the wider edge to be trimmed into register with the shorter edge by the knife, a pivotal mounting for the edge gage to enable the gage to be swung clear of the material and resilient means mounted concentrically with the guide wheel for maintaining the edge gage yieldingly in engagement with the narrower edge of the material.

9. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said

material and located along the line of the seam inserted between the sewing point and the cutting edge of the knife, in combination with a guide comprising a wheel about which one edge of a piping strip is wrapped, mounted between the knife and the point of operation of the stitch forming devices to project a flange on the piping strip between the separated layers of the material, and a mounting block for said guide wheel and the layer supporting member, adjustably mounted for movement in two directions at right angles to each other to vary the projection of the flange on the piping strip between the layers of material and to center the flange of the strip accurately between the said layers.

10. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide comprising a wheel about which one edge of a piping strip is wrapped, mounted between the knife and the point of operation of the stitch forming devices to project a flange on the piping strip between the separated layers of the material, a mounting block for the guide wheel and the layer supporting member, and a pivotally mounted carrier for the mounting block arranged to swing vertically about a horizontal axis.

11. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide comprising a wheel about which one edge of a piping strip is wrapped, mounted between the knife and the point of operation of the stitch forming devices to project a flange on the piping strip between the separated layers of the material, a mounting block for the guide wheel and the layer supporting member, a fixed bracket, a carrier for the mounting block pivotally mounted on the bracket and arranged to swing vertically about a horizontal axis, and a latch supported on one of two parts including the carrier and its mounting bracket and arranged to engage the other of said parts for preventing vertical swinging movement of the carrier from operative position during sewing operations.

12. A sewing machine for operating upon two layers of material, the edge on one of which projects beyond that of another, said machine having stitch-forming devices, an edge gage for

the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide comprising a wheel about which one edge of a piping strip is wrapped mounted between the knife and the point of operation of the stitch forming devices to project a flange on the piping strip between the separated layers of the material, a mounting block for the guide wheel and the layer supporting member, a fixed bracket, a carrier for the mounting block pivotally mounted on the bracket and arranged to swing vertically about a horizontal axis, a latch supported on one of two parts including the carrier and its mounting bracket and arranged to engage the other of said parts for preventing vertical swinging movement of the carrier from operative position during sewing operations, and mechanism for actuating the knife including an oscillating arm, a block on which the knife is supported, a finger pivotally mounted on said arm and arranged to engage or disengage the knife supporting block upon swinging movement about its pivotal mounting, and means for locking the finger from disengagement with the knife block.

13. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide comprising a wheel about which one edge of a piping strip is wrapped mounted between the knife and the point of operation of the stitch forming devices to project a flange on the piping strip between the separated layers of the material, a mounting block for the guide wheel and the layer supported member, a fixed block, a carrier for the mounting block pivotally mounted on the bracket and arranged to swing vertically about a horizontal axis, a latch supported on one of two parts including the carrier and its mounting bracket and arranged to engage the other of said parts for preventing vertical swinging movement of the carrier from operative position during sewing operations, and mechanism for actuating the knife including an oscillating arm, a block on which the knife is supported, a finger pivotally mounted on said arm and arranged to engage or disengage the knife supporting block upon swinging movement about its pivotal mounting, means for locking the finger from disengagement with the knife block, a disconnectable connection for oscillating the arm, and a manually actuated control rod for disconnecting the disconnectable connections and for unlocking the knife actuating finger from the oscillating arm in a single operation, said mounting block carrier acting as a cover for the control rod to block access to said rod when the guide wheel and layer separating member are in operative position.

mounted on said arm and arranged to engage or disengage the knife supporting block upon swinging movement about its pivotal mounting, means for locking the finger from disengagement with the knife block, and a disconnectable connection for oscillating the arm arranged to be released simultaneously with the unlocking action of the finger from the oscillating arm.

14. A sewing machine for operating upon two layers of material, the edge on one of which projects beyond that of another, said machine having stitch-forming devices, an edge gage for the narrower layer, a vibrating trimming knife for the wider layer mounted in close proximity to the edge gage and disposed along the line of the seam inserted adjacent to and in advance of the point of operation of the stitch forming devices to cut said layer, a work support, and a member spaced from the work support in advance of the point of operation of the stitch-forming devices to separate the layers of said material and located along the line of the seam inserted between the sewing point and the cutting edge of the knife, in combination with a guide comprising a wheel about which one edge of a piping strip is wrapped mounted between the knife and the point of operation of the stitch forming devices to project a flange on the piping strip between the separated layers of the material, a mounting block for the guide wheel and the layer supporting member, a fixed bracket, a carrier for the mounting block pivotally mounted on the bracket and arranged to swing vertically about a horizontal axis, a latch supported on one of two parts including the carrier and its mounting bracket and arranged to engage the other of said parts for preventing vertical swinging movement of the carrier from operative position during sewing operations, and mechanism for actuating the knife including an oscillating arm, a block on which the knife is supported, a finger pivotally mounted on said arm and arranged to engage or disengage the knife supporting block upon swinging movement about its pivotal mounting, means for locking the finger from disengagement with the knife block, a disconnectable connection for oscillating the arm, and a manually actuated control rod for disconnecting the disconnectable connections and for unlocking the knife actuating finger from the oscillating arm in a single operation, said mounting block carrier acting as a cover for the control rod to block access to said rod when the guide wheel and layer separating member are in operative position.
